DEVICE FOR ATTACHING LEADS TO LINE WIRES

Edward A. Mack, Huntington, W. Va., assignor to
 Memco Engineering & Manufacturing Co., Inc.,
 Long Island City, N. Y., a corporation of New
 York

Application April 8, 1933, Serial No. 665,181

5 Claims. (Cl. 81—53)

This invention relates to devices for attaching temporary leads to ordinarily inaccessible electric lines.

Line work often requires running a temporary lead to an elevated line. To effect this quickly and conveniently, one end of a lead wire is frequently connected to clamping jaws mounted on the end of a pole of appropriate length to bring the lead wire carrying jaws into gripping position with the line.

The present invention aims to improve existing constructions for such line work and generally stated, takes the form of line wire gripping jaws having a lead wire connected to one of the jaws, the jaws being adapted to be locked to the end of a pole of suitable reach, the rotation of the pole relative to one of the jaws hooked over the line, causing the jaws to open or close and grip or release the line.

More specifically stated, the invention comprises line gripping jaws, one of which is in threaded engagement with a bolt; the bolt head being locked to the end of a pole of suitable length by partial rotation of the head with respect to a polygonal opening through which the bolt head is passed, while the other jaw idles on the shank of the bolt and by end thrust frictionally locks the jaws in gripping position until released by sufficient rotational pressure to overcome the friction lock.

While one embodiment of the invention is shown in the drawing accompanying this application and forming part thereof, it is to be understood that such embodiment is merely illustrative of the underlying principles of the invention so as to afford a clear understanding thereof to those skilled in the art and is not intended as limiting the invention to the specific form disclosed therein.

In the said drawing:

Fig. 1 is a side elevation showing the jaws in open position with one jaw hooked over a line wire.

Fig. 2 is a partly fragmentary vertical section showing the jaws in gripping position.

Fig. 3 is an end elevation partly in section, and Fig. 4 is a section on the line 4—4 of Fig. 1.

Continuing now by way of a more detailed description, a reach pole A formed of any suitable material but preferably having a handling section of insulating material, is capped by a sleeve or housing B. One end of sleeve B is conveniently fitted to a reduced end A' to which it may be permanently pinned in any convenient manner, as, for example, by a transverse pin or rivet

C, while the other end of the sleeve B affords a recess for housing an extensible spring D. One end, of spring D abuts against a transverse wall D' formed in the sleeve B, while the other end rides against one end of a rotatable locking member E which slides longitudinally in the sleeve B and is normally pressed upwardly by spring D. One end of the spring D is held against displacement by a centering boss E' formed at the lower end of the rotatable member E. A polyhedral recess E'' for receiving a bolt head to be described, is formed in the upper end of member E. The member E has one or more radially disposed operable fins or lugs F for manually rotating it, the fins being movable in the clearance provided between the upstanding ends G. In order to confine the spring pushed member E within the sleeve B, an end plate H is riveted or otherwise secured to the upstanding ends G and has a polygonal opening J conveniently, although not necessarily, conforming to the shape of a bolt head K adapted to be passed in inverted position through the opening J and into the seating recess E'' formed in the spring pressed rotatable member E. The top of the bolt head K when seated is located below the level of the top plate. In order to hold the member E in various angular rotational positions, it has one or more upstanding nibs J' adapted to lock with indents J'' forming an arrangement for latching the member E to plate H. The bolt head K has a shank L extending through opening J and one end of the shank is in threaded engagement with jaw M, the latter having a laterally projecting guide hook M', adapted to be initially hooked over a line wire M' to guide the line wire to proper position for gripping. A slight downward pressure on the reach pole prevents rotation of the jaw M when the threaded shank L of the bolt is rotated by rotation of the pole. Conveni- 40

ently formed with jaw M and oppositely disposed to the hook M', a clamping plate N is secured to an inclined face, preferably cast with the jaw M to lock one end of a lead wire P in place, the inclined arrangement of clamping plate and face 45 throwing the free end of the lead away from the pole. The lead wire clamping plate N may be held in position in any convenient manner, as, for instance, by the clamping screws R. In order to prevent the lower jaw member S from rotating with respect to the upper jaw M, which is prevented from rotating by the hook being pressed on the line wire as heretofore indicated, the lower jaw S is slidably keyed at S' to the upper jaw M and is loosely fitted on the bolt shank. vent separation of jaw S from the shank, it is keyed to an annular groove S' formed intermediate of the shank. Motion of jaw S is stopped by a collar T formed with the bolt and which is spaced from the bolt head K so that the collar will bear on the top surface of the end plate H when the bolt head is located below the plate. In order that the jaw S and jaw M may be frictionally held in locked position after the line wire 10 is gripped, a lock washer T' is placed between the end of the jaw S and the collar T, as will be readily understood.

When it is desired to connect the lead wire P to the line wire M'', the bolt head K is passed 15 through the end plate H of reach pole A and seated in recess E''. Lateral pressure is then applied to the wings G to rotate the member E together with the bolt head K. The corners of the bolt head no longer conform to the opening J in 20 the end plate H and in this latched position of the member E, cannot separate from the end of the reach pole A. The end of the reach pole A having the attached unit is then raised until the hook M' is hooked over the line wire M'', the pole A is 25 rotated with a downward pull, causing the jaws to advance toward each other to grip the line wire M''. Longitudinal motion of the jaw S being arrested by abutment against line wire M'', the end thrust against the lock washer T' and collar 30 T prevent the jaws from opening except on definite pressure and the connection established through lead wire P may be used as desired. To release the jaws, the reach pole A is rotated in reverse direction.

35 I claim:

1. A stick for use in devices for temporarily attaching leads to line wires comprising a manipulating pole having a sleeve fitted on one end thereof, the sleeve having a plurality of projecting ends, an end plate secured to the projecting ends and having a polygonal opening, and a rotatable member in the sleeve having a polyhedral recess coaxial with the plate opening, the rotatable member having manually operable fins 40 projecting between the projecting ends, and the plate and end of the sleeve to rotate the rotatable member relatively to the plate.

2. A stick for use in devices for temporarily attaching leads to line wires comprising a manipulating pole having a sleeve fitted on one end thereof, the sleeve having a plurality of projecting ends, a flat end plate secured to the projecting ends and having a polygonal opening, a rotatable member 45 in the sleeve having a polyhedral recess coaxial with the plate opening, and a spring bearing

against one face of the rotatable locking member to normally press the rotatable member against the end plate, the rotatable member having manually operable outwardly projecting fins to rotate the member relatively to the plate.

3. A stick for use in devices for temporarily attaching leads to line wires comprising a manipulating pole having a sleeve fitted on one end thereof, the sleeve having a plurality of projecting ends, a flat end plate secured to the projecting ends and having a polygonal opening, a rotatable member in the sleeve having a polyhedral recess coaxial with the plate opening and an axially located spring centering boss at the opposite end, and a spring having one end centered by the boss 10 and bearing against one face of the rotatable locking member to normally press the rotatable member against the end plate, the rotatable member having manually operable outwardly projecting fins to rotate the member relatively to the 15 plate.

4. A stick for use in devices for temporarily attaching leads to line wires comprising a manipulating pole having a reduced end, a sleeve fitted on the reduced end having a transverse partition 20 resting on the pole end and having a plurality of upstanding ends, a flat end plate secured to the upstanding ends having locking indents on one face thereof and an axial polygonal opening, a rotatable member in the sleeve having a polyhedral recess coaxial with the plate opening and projecting ribs formed on the end of the rotatable member to engage the indents of the plate to lock the rotatable member in rotated position, an axially located spring centering boss at the 25 opposite end of the rotatable member, and a spring having one end centered by the boss and bearing against one face of the rotatable member and the other end bearing against the transverse partition of the sleeve to normally press the rotatable member against the end plate, the rotatable member having manually operable fins projecting beyond the sleeve for rotating the rotatable member relatively to the plate.

5. A stick for use in devices for temporarily attaching leads to line wires comprising a manipulating pole having a sleeve on one end thereof, the sleeve having a plurality of projecting ends, an end plate secured to the projecting ends and having an opening, a rotatable locking member 50 in the sleeve having a recess of non-circular cross-section adapted to register with the plate opening and having a manually operable outwardly projecting fin between the projecting ends.
